UNITED STATES PATENT OFFICE.

ROY HERBY IRWIN, OF STANFIELD, OREGON.

FILING DEVICE.

1,158,808.

Specification of Letters Patent.

Patented Nov. 2, 1915.

Application filed October 16, 1914. Serial No. 866,931.

To all whom it may concern:

Be it known that I, ROY H. IRWIN, a citizen of the United States, and a resident of Stanfield, county of Umatilla, State of Oregon, have invented a new and Improved Filing Device, of which the following is a full, clear, and exact description.

My invention relates to a filing element which may be embodied in the form of a drawer, or a like portable structure, a plurality of the drawers being fitted in a cabinet, in practice.

The prime object of my invention is to provide a drawer or the like which is arranged to contain papers in bulk, while an auxiliary compartment beneath the main holder is adapted to receive a single paper, means being provided whereby the front end of the single paper will be positioned to display indicia thereon at the front of the filing element.

The main holder may contain legal forms, one of such forms being received in the auxiliary compartment with the caption or heading visible at the front of the filing element, thus indicating the character of the filing papers without opening the drawer. In the case of correspondence files the auxiliary compartment will receive the last communication, in a manner that the name of the party addressed and the date of the letter will be visible at the front, the object being to show the date of the last communication, without opening the drawer, and display it as an index to the name of the correspondent. The device may be employed also for the filing of charge slips, credit memorandum, and as an aid to book-keeping, the charge slips or the like being filed as follows, to wit:

When the slip is received it is at once filed in the auxiliary compartment with the name and file number visible, as well as the amount of the purchase, and the account to date, if so desired. When an additional slip is to be filed the first slip or memorandum will be removed from the auxiliary compartment and placed in the main container, usually in the form of a tray, and so on in succession as the slips or the like are received. The result will be that the slips will be kept in the proper chronological order, and may be self-indexing.

The invention also has for its object to improve filing devices in various particulars whereby to promote convenience in the

use of the device, as well as providing a simple and durable structure.

The invention will be particularly explained in the specific description following.

Reference is had to the accompanying drawings forming part of this specification, in which similar characters of reference indicate corresponding parts in all the views, and in which:

Figure 1 is a perspective view showing a portion of the cabinet with my improved filing elements, one of the latter being shown partly open and the other closed. Fig. 2 is a longitudinal vertical section of one of the elements, and Fig. 3 is a perspective view of the stop device in the auxiliary compartment to properly position a paper in the latter.

Referring to the illustrated construction, the body 10 of my filing element is preferably in the form of a sliding drawer, any convenient number of which may be assembled in a cabinet 11, of approved design. The front 12 of the body 10 is hinged at its lower end, as at 13, to be swung downwardly from the closed position shown in Fig. 2 to the lowered position shown in Fig. 1, and said front is provided with a knob 14, or the like. The ends of the front 12 are rabbed at the sides, as at 15, to engage the front ends of the sides of the body 10.

In connection with the body 10 a main holder 16 is employed, preferably in the form of a tray, which is hinged at its rear end, as at 17, to the transverse back 10^a of the drawer body. The tray 16 is made with an open front, and the sides thereof terminate short of the front end of the drawer 10 to conform to the rabbed ends 15 on the front 12. The bottom 18 of the tray 16 is spaced above the bottom of the drawer 10 to provide an intermediate auxiliary compartment 19, which is designed to receive a single paper B, while the bulk of the papers A are accommodated in the tray 16 above. The available or effective space in the auxiliary compartment 19 terminates short of the rear end of the tray 16.

In the example shown I have provided a stop 20 on the bottom of the drawer 10 against which the rear end of the paper B will contact to limit the rearward movement of said paper. The said stop as shown best in Fig. 3, may be formed of sheet metal 11^a bent to provide a bottom and three sides, there being holes 21 to receive screws or

equivalent fasteners to secure the stop to the proper position on the bottom of the drawer 10.

The hinged front 12 is provided with a transparent portion 21 which may consist of glass, and at the back of the said front 12, or within the same between the front and the forward end of the tray 16, a space 22 is provided which is complementary to the auxiliary compartment 19 and forms an upward extension of the latter in front of the tray 16. The arrangement is such that a paper B placed in the compartment 19 will lie with its rear end against the stop 26, while the forward end, as clearly shown in Figs. 1 and 2, will project beyond the tray 16. When now the front 12 is swung upwardly, the front end of the paper B will extend upwardly at the interior of the transparent portion 21, so that any indicia on said paper, such as the words "Memorandum of payments, file No. 9" will serve to indicate the nature of the paper.

Having thus described my invention, what I claim as new and desire to secure by Letters Patent is:

1. An individual filing element comprising a body, and a holder in the body presenting the major containing space of the filing element and adapted to contain a quantity of papers, there being an auxiliary paper receiving compartment beneath the holder, between the same and the bottom of the body and extending to the front of the said holder, the front of the body and the front end of the holder defining an intervening space complementary to the auxiliary compartment and forming an upward extension thereof, whereby a paper will be accommodated jointly by the auxiliary compartment and said complementary front space to dispose the front end of the paper in indicating position.

2. An individual filing element comprising a body, and a holder movably supported in the body and presenting the major containing space of the filing element, the said holder being spaced above the bottom of the holder to form an auxiliary paper receiving compartment, said compartment being of less length than the containing space of the holder and there being a space in front of the holder complementary to the said compartment.

3. An individual filing element compris-

ing a body, a holder in the body presenting the major containing space of the filing element whereby to hold a quantity of papers, the holder being spaced from the bottom of the body to form an auxiliary paper receiving compartment, and being movable relatively to the body to afford access to the said compartment from the top, said compartment terminating at its rear end forward of the rear end of the holder, and there being a space in front of the holder complementary to the said compartment and forming an upward extension thereof.

4. An individual filing element comprising a body, and a holder movably supported in the body above the bottom thereof to form an auxiliary compartment beneath the holder, and a front on the body hinged to swing toward and from the holder, said hinged front defining a space complementary to the said compartment and extending upwardly therefrom in front of the holder.

5. An individual filing element comprising a body, a tray hinged at its rear end to the body, the said tray presenting the major containing space of the filing element and being spaced above the bottom of the holder to form an intervening auxiliary paper receiving compartment, the said body having a front hinged to swing toward and from the front of the tray and forming a closure to the front of the auxiliary compartment, the said hinged front having a transparent portion and there being a space at the back of the hinged front to accommodate the front end of a paper placed in the compartment.

6. An individual filing element comprising a body in the form of a drawer, a tray hinged at its rear end to the drawer and spaced from the bottom of the latter to form an auxiliary paper receiving compartment, a stop in the compartment positioned forward of the rear end of the tray, and a hinged front on the drawer, there being a space at the back of the said hinged front complementary to and forming an upward extension of the said compartment.

In testimony whereof I have signed my name to this specification in the presence of two subscribing witnesses.

ROY HERBY IRWIN.
